RICHARD STUART HILL, OF LOUISVILLE, KENTUCKY, ASSIGNOR TO BECKWITH ORGAN COMPANY, INCORPORATED, OF LOUISVILLE, KENTUCKY, A CORPORATION OF KENTUCKY.

PEDAL-ACTUATED STOP MECHANISM FOR MUSICAL INSTRUMENTS.

No. 888,400.

Specification of Letters Patent.

Patented May 19, 1908.

Application filed December 30, 1907. Serial No. 408,599.

To all whom it may concern:

Be it known that I, RICHARD STUART HILL, a citizen of the United States, residing at Louisville, in the county of Jefferson and 5 State of Kentucky, have invented a new and useful Pedal-Actuated Stop Mechanism for Musical Instruments, of which the following is a specification.

This invention relates to stop actions for 10 organs, pianos and the like musical instruments, and the objects of my improvement are, simplicity of construction, durability, effectiveness, and ease and comparative inexpensiveness of manufacture. These objects I attain by means of the device illustrated in the accompanying drawings, in which—

Figure 1 is a perspective view; Fig. 2, a detail sectional view in elevation showing the 20 stop off; Fig. 3, a detail sectional view in elevation showing the stop on; and, Fig. 4, a detail front view.

Similar reference numerals refer to similar parts throughout the several views of the 25 drawings.

My invention is embodied in a transmitting lever 1, for transmitting motion from a pedal to the particular stop to be operated. I have shown my invention as embodied in a 30 cabinet organ for the purpose of actuating the octave couplers with the foot instead of with the hand as is customary. This purpose, however, has been accomplished heretofore in a different way and I do not desire 35 to claim as my invention broadly mechanism for this purpose. The transmitting lever 1 consists preferably of a piece of wire or metal rod bent into the form shown in the drawing, that is, having a portion in the form 40 of a bail, as shown at 1, two straight portions in axial line, which are pivoted, the one in a bearing block 2 secured to board 3, and the other in a bearing block 4 fastened to a cleat 5, which in turn is secured to the inner side 45 of the end portion 6 of the organ case 7. The portion which passes through bearing block 4 is then extended as member 8 of the lever at right angles to the pivoted portion and terminates in a finger 9 parallel with the 50 pivot portions. Thus an integral lever is produced, the one end of which terminates in the bail shown at 1 and the other portion 8 terminating in finger 9 and fulcrumed in block 4.

A connecting bar 10, provided with a 55 hooked end 11, engages the bail of lever 1 by means of its hook. The end of bar 10 opposite the hook is attached to the outer crank-portion of a crank-rod 12 which is journaled in a block 13 and is provided at its inner end 60 with a crank adapted to bear against the under surface of the board 14 which carries the octave couplers. Motion is imparted to the transmission lever 1, and through it to the stop, from a pedal lever 15, which is operatively connected with a double crank rock-bar 16. The bar 16 in turn is operatively connected with an upright double-hook bar 18. The bar 18 is kept in its normally raised position by a spring 17 attached at one of its 70 ends to the bar and at its other to the end of case 7. Bar 18 is provided at its upper end with a forward extending and a backward extending hook adapted to engage the finger 9 and the bail of lever 1 respectively on its 75 descent.

The operation of the device is as follows:— When the octave couplers are out of commission the board 14 lies flat as shown in Fig. 2. If it is desired now to throw the octave coupler on, the pedal 15 is pressed down, rotating rock-shaft 16 and drawing bar 18 downward. It will be seen that, in its descent, bar 18 engages with its rearward extending hook the bail of lever 1 and slips backward to such a 80 position that the bail fits into the angle of the hook and close against the rear edge of the bar. When this occurs, the forward hook is 85 out of line with finger 9, and, therefore, when the bail of lever 1 is drawn downward, finger 9 at the opposite end of the lever rises, and the forward hook in its descent does not engage finger 9 but passes to its rear. As shown in Fig. 3, when the bail of lever 1 is 90 down, bar 10 is on a dead center, or its hook 95 is slightly below the fulcrum of the lever, so that the device is locked in that position, and board 14 is held in the raised position, so that the coupler stop is on until further actuated by the performer. When the pedal is released (Fig. 3) bar 18 rises and swings forward to its normal central position relative to the lever 1. In this position the forward hook of lever 18 is above and ready to engage finger 9. If now it is desired to throw the 100 octave coupler out of commission, the performer may do so by pressing upon pedal 15 when the forward hook of bar 18 engages and 105

draws down finger 9, thereby raising the bail and allowing rod 10 to come forward and drop the coupler board 14.

It will be understood that, in as much as lever 1 comprises the bail, lever 8, and finger 9 in one piece, there is no possibility of lost motion developing between these members and they therefore always operate and remain in the same relation. The lever in this form is also easily, quickly, and cheaply made, being preferably made in a wire forming machine. It is easily mounted, because, the wire, being already round, is in a suitable form for being pivoted in the blocks.

Having thus described my invention so that any one skilled in the art pertaining thereto may make and use it, I claim—

An organ comprising in combination, a case, a pedal, an octave coupler, a vertical bar operatively connected with said pedal, 20 said bar provided at its upper end with a forward-facing hook and a rearward-facing hook, a transmission-lever mounted in said case and operatively connected with said octave coupler, said transmission-lever comprising integrally a bail at one end in operative relation with said rearward-facing hook, and a finger at its opposite end in operative relation with said forward-facing hook: 25

RICHARD STUART HILL.
